[57] **ABSTRACT**

A method of and apparatus for receiving a wound coil from a winding device, having a rotating block on which a longitudinal member is wound into the wound coil, is disclosed.

The wound coil receiving apparatus or device has a hook provided with a toe portion and a body portion. A hook positioning member is provided with a toe portion receiving aperture adapted to receive the toe portion in projecting alignment with the wound coil so that the wound coil may be transferred from the block to the toe portion.

The method includes the steps of positioning a hook having a toe portion and a body portion in a toe portion receiving aperture of a hook positioning member so that the toe portion projects from the toe portion receiving aperture in projecting alignment with the wound coil on the block and transferring the wound coil from the block to the positioned toe portion.

METHOD OF AND APPARATUS FOR RECEIVING A WOUND COIL

BACKGROUND OF THE INVENTION

Heretofore, a longitudinal member, such as a wire, rod, or the like, has been wound into a wound coil or bundle on a winding apparatus of the type shown in U.S. Pat. No. 2,655,323, issued Oct. 13, 1953, to Wiggan and assigned to the same assignee as the present application. The coil winding apparatus comprises a generally rotatable horizontal shaft on which a continuously rotating takeup block is mounted. After attaching a free end of the longitudinal wire, rod, or the like to the continuously rotating takeup block, the longitudinal member is wound into a wound coil or bundle on the rotating takeup block. After a predetermined mount of wire has been wound, such as about 200 to 2,000 pounds of wire, the operator cuts one of the last wound turns of the coil to form a wound coil or bundle of predetermined weight. Previously, the wound coil was stripped by the operator onto a free swinging hoist hook, which hook was unstable to control and unsafe for the operator.

Later, as shown in the above-mentioned U.S. Pat. No. 2,655,323, the takeup block was provided with a swivelable eye and a chain (having a snap hook at one end) was connected to the centrally mounted eye. The other end of the chain was attached, by means of a ring, to the hoist hook. In operation, the operator would remove the wound coil from the rotating takeup block with the chain passing through the wound coil and deposit the wound coil on the floor adjacent the rotating winding machine. The snap hook was then unfastened from the eye and connected to the ring adjacent the frame hoist hook, whereupon the wound coil was raised by the hoist and transported to another location.

OBJECTS OF THE INVENTION

It is the general object of this invention to avoid and overcome the foregoing and other difficulties of and objections to prior art practices by the provision of an improved method of and apparatus for receiving a wound coil from a coil winding machine, which method and apparatus:

- a. eliminate the step of depositing the wound coil on the floor adjacent the coil winding machine preparatory for the transfer operation;
- b. eliminate the use of the eye, snap hook, chain, and ring employed in conventional transfer devices;
- c. position the hoist hook in a stable position where it is easy to control during the transfer operation;
- d. eliminate the operator hazards formerly associated with the conventional transfer devices;
- e. provide apparatus which is simple and rugged in construction;
- f. handle a wide range of weights of wound coils; and
- g. completely eliminate danger of injury to the operator of the coil winding machine during the transfer operation.

BRIEF SUMMARY OF THE INVENTION

The aforesaid objects of this invention, and other objects which will become apparent as the description proceeds are achieved by providing an improved method of and apparatus for receiving a wound coil from a coil winding machine.

The wound coil receiving apparatus or device has a hook provided with a toe portion and a body portion. A hook positioning member is provided with a toe portion receiving aperture adapted to receive the toe portion in projecting alignment with the wound coil so that the wound coil may be transferred from the block to the toe portion.

This method includes the steps of positioning a hook having a toe portion and a body portion in a toe portion receiving aperture of a hook positioning member so that the toe portion projects from the toe portion receiving aperture in projecting alignment with the wound coil on the block, and transferring the wound coil from the block to the positioned toe portion.

BRIEF DESCRIPTION OF THE SEVERAL VIEWS OF THE DRAWINGS

For a better understanding of this invention, reference should be had to the accompanying drawings wherein like numerals of reference indicate similar parts throughout the several views and wherein:

5 FIG. 1 is a side elevational view of the improved wound coil receiving apparatus or device and showing a hook connected to a hoist chain, the hook having a toe portion and a body portion, and a hook positioning member provided with a toe portion receiving aperture adapted to receive the toe portion in projecting alignment with a cut wound coil on a rotating takeup block of a coil winding machine;

10 15 FIG. 2 is a side elevational view of the hook shown in FIG. 1 and showing in greater detail a handle, a stop lug on the body portion of the hook and a pivot lug on the lower portion of the body portion of the hook adjacent the heel of the hook between the body portion and the toe portion;

20 20 FIG. 3 is an enlarged horizontal sectional view taken along the line 3—3 of FIG. 2 in the direction of the arrows and showing the stop lug on the body portion of the hook;

25 25 FIG. 4 is an enlarged side elevational view of the hook positioning member shown in FIG. 1 and showing lug receiving apertures spaced from the toe portion receiving aperture and reinforcing members on the hook positioning member between the lug receiving apertures and the toe portion receiving aperture;

30 30 FIG. 5 is an enlarged top plan view taken of the hook positioning member taken along the line 5—5 of FIG. 4 in the direction of the arrows;

35 35 FIG. 6 is a fragmentary side elevational view similar to FIG. 4 of an alternative embodiment of the hook positioning member showing either a removable or fixed stop lug on the hook positioning member and a fixed pivot lug secured to the bottom of the lug receiving aperture of the hook positioning member;

40 40 FIG. 7 is a view similar to FIG. 6 of another alternative embodiment of the hook positioning member showing a removable pivot lug disposed through suitable holes in the forward portion of the hook positioning member adjacent the inner portions of the heel between the body portion and toe portion of the hook, and a stop lug of the removable type disposed in suitable holes in the hook positioning member to engage the back side of the body portion of the hook; and

45 45 FIG. 8 is a view similar to FIGS. 6 and 7 showing a further alternative embodiment of the wound coil receiving device wherein a removable stop lug or lugs is positionable in a suitable hole or holes in the hook positioning member to engage a slot in the body portion of the hook and showing further a removable pivot lug or lugs similarly disposed in the hook positioning member.

50 50 Although the principles of this invention are broadly applicable to the transfer of heavy hollow articles from a processing machine, this invention is particularly adapted for use in conjunction with a machine for winding a coil from a longitudinal member and hence it has been so illustrated and will be so described.

DETAILED DESCRIPTION

With specific reference to the form of this invention illustrated in the drawings, and referring particularly to FIG. 1, a winding machine or device is indicated generally by the reference numeral 10.

60 65 70 75 This winding device 10 (FIG. 1) has a continuously rotating takeup block 12 (FIG. 1) mounted on a horizontal shaft 14 (FIG. 1) projecting from a frame or stationary portion 16 (FIG. 1) of the winding device 10. As shown in FIG. 1, a wound coil 18 has been severed from a coil 18a (FIG. 1) being wound on the winding device 10 and such wound coil 18 has been moved to the left-hand portion (FIG. 1) of the block 12 preparatory for its removal from the continuously rotating takeup block 14. A wound coil receiving apparatus or device

20 (FIGS. 1-5) is disposed to the left of the block 12 and is positioned as hereinafter explained to receive the wound coil 18.

WOUND COIL RECEIVING DEVICE 20

This wound coil receiving device 20 (FIGS. 1-5) has a hook 22 (FIGS. 1-3) provided with a toe portion 24 (FIGS. 1-3) and a body portion 26 (FIGS. 1-3). An upper portion 28 (FIGS. 1,2) of the body portion 26 is provided with a suitable hole 30 (FIGS. 1,2) so that a ring 32 (FIG. 1) may connect the hook 22 to a hoist hook 34 (FIG. 1) attached to a chain 36 (FIG. 1) of a hoist (not shown).

A hook positioning member 38 (FIGS. 1,4,5) is provided with a toe portion receiving aperture 40 (FIGS. 1,4,5) which aperture 40 is adapted to receive (as shown in FIG. 1) the toe portion 24 in projecting alignment with the wound coil 18 on the left-hand portion, as viewed in FIG. 1, of the block 12 so that the wound coil 18 may be transferred from the block 12 to the toe portion 24 of the hook 22. It will be noted from a consideration of FIG. 1 that the toe portion 24 seats on the bottom 40a (FIGS. 1,4,5) of the toe portion receiving aperture 40 and that the receiving end 24a (FIGS. 1,2) of the toe portion 24 is disposed laterally a clearance distance C₁ away from the left-hand end (FIG. 1) of the block 12 and is further disposed a clearance distance C₂ (FIG. 1) below the top of the block 12.

As shown in FIGS. 1, 2 and 3, the wound coil receiving device 20 has a pivot lug 42 projecting from a heel portion 44 (FIGS. 1,2) between the body portion 26 and the toe portion 24 of the hook 22. The hook positioning member 38 is provided with a lug receiving aperture or apertures 46 (FIGS. 1,4,5) angularly spaced, as shown in FIG. 5, from the toe portion receiving aperture 40. The pivot lug 42 is adapted to seat itself in the bottom (FIG. 1) of the lug receiving aperture 46 to prevent the body portion 26 of the hook 22 from moving out of the toe portion receiving aperture 40.

In addition, the body portion 26 of the hook 22 is provided with a stop lug 48 (FIGS. 1,2,3) which engages the side wall 50 (FIGS. 1,4,5) of the lug receiving aperture 46 to prevent 40 downward rotation of the toe portion 24 when the coil 18 is removed from the left-hand portion, as viewed in FIG. 1, of the block 12, and transferred to the toe portion 24 of the hook 22.

As shown in FIGS. 1 and 2, the body portion 26 of the hook 22 is provided with a handle 52 to facilitate manipulation of the hook positioning member 38 by the operator. As shown in FIGS. 4 and 5, the hook positioning member 38 may be provided with reinforcing members 54, suitably angles or the like, secured to the hook positioning member, as by welding or the like, between the toe portion receiving aperture 40 (FIG. 5) and the lug receiving apertures 46 (FIG. 5).

MOUNTING MEANS

Referring again to FIG. 1, it will be noted that the hook positioning member 38 is mounted on a mounting member, such as a pipe 56 (FIGS. 1,4) or the like, by means of a rivet, screw, bolt 58 (FIGS. 1,4) or the like. Such pipe 56 projects from a socket 60 (FIG. 1) disposed in a suitable hole 62 (FIG. 1) in a foundation or floor 63 (FIG. 1) for supporting the coil winding device 10. For the purpose of preventing rotation of the pipe 56, and hence the hook positioning member 38, the lower portion of the pipe 56 is provided with a slot 64 (FIG. 1), which slot 64 straddles a pin or rod 66 (FIG. 1) positioned in the bottom of the side walls of the socket 60.

ALTERNATIVE EMBODIMENTS

It will be understood by those skilled in the art that alternatively as shown in FIG. 6, a stop lug 48⁶ (suitable a removable or fixed pin or the like) may be positioned in a hole or holes 68 in the side wall of the hook positioning member 38⁶ to engage the forward surface of the body portion 26 of the hook 22. In addition, a pivot lug 42⁶ may be secured, as by welding or the like, to the bottom of the lug receiving aperture 46.

In FIG. 7, the lug receiving aperture 46, as shown in FIGS. 1-6, is eliminated and a stop lug or pin 48⁷ is positioned in a suitable hole or holes 68 in the side wall of the hook positioning member 38⁷ to engage the rearward sides of the body portion 26 of the hook 22. A pivot lug 42⁷ of the removable type may be inserted in suitable holes 70 in the hook positioning member 38⁷ so that such pivot lug 42⁷ engages the inward portions of the heel portion 44 of the hook 22.

In FIG. 8, the body portion 26⁸ of the hook 22⁸ is provided with a longitudinal slot 72. A stop lug or pin 48⁸ is removably inserted into a hole 68 in the hook positioning member 38 to engage the slot 72. In like manner, a removable pivot lug or pin 42⁸ is inserted through a hole 70 in the hook positioning member 38⁸ to similarly engage the lower portion of the slot 72 thereby securely positioning the hook 22⁸ in the desired position.

It will be understood by those skilled in the art that the stop lugs 48⁶ (FIG. 6), 48⁷ (FIG. 7), and 48⁸ (FIG. 8) and the pivot lug 42⁶ (FIG. 6), 42⁷ (FIG. 7), and 42⁸ (FIG. 8) may be of any desired cross section, such as concave arcuate, convex arcuate, hexagonal, octagonal, square, rectangular, hyperbolical, parabolical, elliptical, or the like and inserted or fixed in holes 68 and 70 which holes 68 and 70 are adapted to receive them.

It will be understood by those skilled in the art from the above description of the apparatus that an improved method of receiving a wound coil 18 is provided.

METHOD

30 The improved method includes the steps of positioning a hook 22 (FIGS. 1,2) having a toe portion 24 and a body portion 26 in a toe portion receiving aperture 40 in a hook positioning member 38 (FIGS. 1,4,5) so that the toe portion 24 projects therefrom in alignment with a block 12 on which the wound coil 18 has been wound, and transferring the wound coil 18 from the block 12 to the toe portion 24.

SUMMARY OF THE ACHIEVEMENTS OF THE OBJECTS OF THE INVENTION

It will be recognized by those skilled in the art that the objects of this invention have been achieved by providing an improved method of and apparatus 20 (FIGS. 1-5), 20⁶ (FIG. 6), 20⁷ (FIG. 7), and 20⁸ (FIG. 8) for receiving wound coils 18 from a coil winding machine 10, which method and apparatus 20 (FIGS. 1-5), 20⁶ (FIG. 6), 20⁷ (FIG. 7) and 20⁸ (FIG. 8) eliminate the step of depositing the wound coil 18 on the floor 63 adjacent the coil winding machine 10 preparatory for the transfer operation; eliminate the use of the eye, snap hook, chain, and ring employed in conventional transfer devices; position the hoist hook 22 in a stable position where it is easy to control during the transfer operation; eliminate the hazards formerly associated with the conventional transfer devices; provide apparatus 20, 20⁶, 20⁷, 20⁸, which are simple and rugged in construction; handle a wide range of weights of wound coils 18; and completely eliminate danger of injury to the operator of the coil winding machine 10 during the transfer operation.

While in accordance with the patent statutes, preferred and alternative embodiments of this invention have been described and illustrated in detail, it is to be particularly understood that the invention is not limited thereto or thereby.

We claim:

1. For a winding device having a block and for winding a longitudinal member into a wound coil on said block, a wound coil receiving device having:
  - a. a hook having a toe portion and a body portion, and
  - b. a hook positioning member provided with a toe portion receiving aperture adapted to receive said toe portion in projecting alignment with said wound coil on said block so that said wound coil may be transferred from said block to said toe portion.
2. The wound coil receiving device recited in claim 1 wherein said body portion has a pivot lug projecting therefrom and said hook positioning member is provided with a lug

receiving aperture angularly spaced from said toe portion receiving aperture,

a. said lug receiving aperture being adapted to receive said pivot lug to prevent said body portion from moving out of said toe portion receiving aperture.

3. The wound coil receiving device recited in claim 1 wherein said hook positioning member is provided with a lug receiving aperture angularly spaced from said toe portion receiving aperture, and said body portion has a stop lug,

a. said stop lug engaging the side wall of said lug receiving aperture to prevent downward rotation of said toe portion when said wound coil is moved onto said toe portion.

4. The wound coil receiving device recited in claim 1 wherein said hook has a handle.

5. The wound coil receiving device recited in claim 2 wherein said body portion has a stop lug spaced from said pivot lug,

a. said stop lug engaging the side wall of said lug receiving aperture to prevent downward rotation of said toe portion when said wound coil is moved onto said toe portion.

6. The wound coil receiving device recited in claim 2 and having a reinforcing member between said toe portion receiving aperture and said lug receiving aperture.

7. The wound coil receiving device recited in claim 1 wherein said hook positioning member has a pivot lug engaging said hook to prevent said body portion from moving out of said toe receiving aperture.

8. The wound coil receiving device recited in claim 1 wherein said hook positioning member has a stop lug engaging said hook to prevent downward rotation of said toe portion when said wound coil is moved onto said toe portion.

9. The wound coil receiving device recited in claim 1 wherein said body portion is provided with a lug receiving aperture, and said hook receiving member has a pivot lug engageable with said lug receiving aperture to prevent said body portion from moving out of said toe receiving aperture.

10. The wound coil receiving device recited in claim 1 wherein said body portion is provided with a lug receiving aperture, and said hook receiving member has a stop lug engageable with said lug receiving aperture to prevent

10 downward rotation of said toe portion when said wound coil is moved onto said toe portion.

11. A method of receiving a coil wound on a block of a winding device including the steps of:

5 a. positioning a toe portion of a hook in a toe portion receiving aperture of a hook receiving member so that the toe portion extends in projecting alignment with said wound coil on said block; and

b. transferring said wound coil from said block to said toe portion.

12. The method recited in claim 11 including the step of positioning a pivot lug on a body portion of said hook in a lug receiving aperture in said hook positioning member to prevent said body portion from moving out of said toe portion receiving aperture.

15 13. The method recited in claim 11 and including the step of manipulating the hook receiving member by means of a handle on said hook positioning member.

14. The method recited in claim 12 including the step of 20 reinforcing said hook positioning member between said toe portion receiving aperture and said lug receiving aperture.

15 15. The method recited in claim 11 and including the step of engaging said hook with a pivot lug on said hook positioning member to prevent said body portion from moving out of said toe receiving aperture.

16. The method recited in claim 11 and including the step of 25 engaging said hook with a stop lug on said hook positioning member to prevent downward rotation of said toe portion when said wound coil is moved onto said toe portion.

17. The method recited in claim 11 and including the step of moving a pivot lug on said hook receiving member into engagement with a lug receiving aperture on said body portion to prevent said body portion from moving out of said toe receiving aperture.

18. The method recited in claim 11 and including the step of 30 moving a stop lug on said hook receiving member into engagement with a lug receiving aperture on said body portion to prevent downward rotation of said toe portion when said wound coil is moved onto said toe portion.
